UNITED STATES PATENT OFFICE.

BENJAMIN B. FREEMAN, OF CAMBRIDGE, MASSACHUSETTS.

DESIGN FOR A SPOON.

SPECIFICATION forming part of Design No. 20,774, dated May 26, 1891.

Application filed March 17, 1891. Serial No. 385,426. Term of patent 3½ years.

To all whom it may concern:

Be it known that I, BENJAMIN B. FREEMAN, of Cambridge, in the county of Middlesex, State of Massachusetts, have invented and produced a new and original Design for Spoons, of which the following is a full, clear, and exact description, reference being had to the accompanying photograph or fac-simile, in which a face view of the spoon is shown.

10 The leading features of my design comprise the representation of a statue on the face of the head of the spoon-handle.

15 The bowl A of the spoon is of the ordinary oval form, and the shank B projects in a straight line therefrom for a determined distance. At x the shank is bent or curved laterally, the head C of the handle being in line with the body of the shank. The face of the head C bears a representation of a statue in

relief, in which the figure is represented as seated in a chair and mounted on a pedestal y. From the bend x in the handle scroll-work in relief surrounds the representation of the statue. The edges of the handle-head are escalloped irregularly and the scrolls approximately following the curves of said escallops.

Having thus described my design, what I claim is—

The design for a spoon, substantially as herein shown and described, which consists primarily in the representation on the face of a spoon-handle of a statue comprising a seated male figure mounted on a pedestal, substantially as described.

BENJAMIN B. FREEMAN.
